(57) **CLAIM**

The ornamental design for a barbell, as shown and described.

DESCRIPTION

This application is an application for reissue of U.S. Pat. No. D843,524, issued Mar. 19, 2019, which corresponds to U.S. patent application Ser. No. 29/605,895, the entire contents of which are incorporated herein by reference. Application '895 is a continuation of U.S. pat. app. Ser. No. 29/504,413, filed Oct. 6, 2014, entitled Barbell, the entire contents of which is hereby incorporated by reference.

[FIG. 1 of the drawings is a front perspective view of the barbell with an elastic band positioned in the channel showing, in particular, the ornamental design thereof.]

[FIG. 2 of the drawings is a back perspective view thereof.]

[FIG. 3 of the drawings is a front elevational view thereof.]

[FIG. 4 of the drawings is a back elevational view thereof.]

[FIG. 5 of the drawings is a top plan view thereof.]

[FIG. 6 of the drawings is a bottom plan view thereof.]

[FIG. 7 of the drawings is a cross-sectional view taken generally about lines 7-7 of FIG. 3.]

[FIG. 8 of the drawings is a front perspective view of the barbell with the elastic band removed from the channel.]

[FIG. 9 of the drawings is a back perspective view thereof with the elastic band removed from the channel.]

[FIG. 10 of the drawings is a front elevational view thereof with the elastic band removed from the channel.]

[FIG. 11 of the drawings is a back elevational view thereof with the elastic band removed from the channel; and]

[FIG. 12 of the drawings is a perspective view of the barbell having the elastic band positioned in the channel.]

FIG. 13 is a front perspective view of a barbell showing my new design with the barbell depicted in a first state showing removable elastic bands located in channels;

FIG. 14 is an enlarged right side perspective detailed view thereof;

FIG. 15 is an enlarged left side perspective detailed view thereof;

(Continued)

(NEW)

*FIG. 16 is an enlarged front detailed view thereof;
 FIG. 17 is another enlarged front detailed view thereof;
 FIG. 18 is a left side elevational view thereof;
 FIG. 19 is a right side elevational view thereof;
 FIG. 20 is a cross-sectional view taken about line 20-20 of FIG. 16;
 FIG. 21 is a front perspective view of the barbell of FIGS. 13-20 shown with the elastic bands removed from the channels;
 FIG. 22 is an enlarged right-side perspective detailed view corresponding to FIG. 14 showing the elastic band removed from the channel;
 FIG. 23 an enlarged left-side perspective detailed view corresponding to FIG. 15 showing the elastic band removed from the channel;
 FIG. 24 is an enlarged front detailed view corresponding to FIG. 16 with the elastic band removed from the channel;
 FIG. 25 is an enlarged front detailed view corresponding to FIG. 17 with the elastic band removed from the channel; and,
 FIG. 26 is a left side perspective detailed view thereof.*

1 Claim, 24 Drawing Sheets

Matter enclosed in heavy brackets [ ] appears in the original patent but forms no part of this reissue; matter printed in italics indicates the additions made by reissue.
